UNITED STATES PATENT OFFICE

MILTON S. SMITH, OF MAPLEWOOD, NEW JERSEY, ASSIGNOR TO CARRIER CONSTRUCTION COMPANY, INC., OF NEWARK, NEW JERSEY

HEAT EXCHANGE DEVICE

Application filed November 27, 1929. Serial No. 410,111.

This invention relates to improvements in steam air heaters, radiators and other heat exchange devices having radiating tubes provided with exterior fins or projections for the purpose of increasing the radiating surface of the device. These radiating fins commonly extend around and project outwardly from the tubes in more or less closely spaced relation to each other and are secured on the tubes so as to have a good heat conducting connection therewith. In some instances the fins are formed by separate thin plates separately applied to and secured on the tubes. Such construction is desirable in heat exchange devices in which, for instance, the tubes have relatively flat faces or are of elongated, elliptical or other non-circular cross sectional shape; in devices in which the tubes are bent between their ends, and in devices in which it is desirable to join the tubes to the headers or fluid connections before securing the fins on the tubes.

It is important that the radiating fins should be soldered, brazed or otherwise secured to the tube so as to have a good heat conducting contact with the surface of the tubes throughout the lengths of the joints between the fins and the tubes, and one method of effecting this result is to apply the fin plates to the tubes and temporarily retain them in place on the tubes in the intended relation, and then dip the tubes having the fin plates thereon in molten solder to permanently solder the plates to the tubes. There are usually a large number of fin plates on each tube and difficulty has been experienced in the production of these devices in retaining the fin plates securely in place and in proper contact with the surfaces of the tube until they are permanently soldered in place, and in preventing deformation of the thin plates during the subsequent operations on the device.

One object of my invention is to provide fin plates of a novel construction adapting them to be readily placed in proper spaced relation to each other on the radiating tubes and retained in the intended positions on the tube until and during the operation of permanently soldering or securing the plates on the tube.

Other objects of the invention are to construct the fin plates so that they can be readily placed and secured on a tube after the latter has been joined at its ends to the headers or fluid inlet and outlet connections, thus permitting the tube to be secured to the headers or fluid connections and tested before securing the fin plates thereon, and thereby avoiding possible injury to or deformation of the fins in the testing or other subsequent operations in the construction of the heat exchange device; also to provide a heat exchange device in which the fin plates are constructed so that they can be readily slipped over the tube laterally thereof, and securing means are provided whereby the fin plates can be readily retained in place on the tube preparatory to being soldered or permanently secured in place; also to improve heat exchange devices in the other respects hereinafter described and set forth in the claims.

In the accompanying drawings:

Fig. 1 is a plan view of a tubular heater having a bent, flat-sided tube equipped with fin plates and embodying my invention.

Fig. 2 is a fragmentary, side elevation thereof.

Fig. 3 is a transverse, sectional elevation thereof on line 3-3, Fig. 1.

Fig. 4 is a face view, on an enlarged scale, of one of the fin plates showing the two parts of the split end of the plate secured together but omitting the tube.

Fig. 5 is an enlarged end elevation of two adjacent fin plates.

Fig. 6 is a sectional plan on a still larger scale on line 6-6, Fig. 3.

Fig. 7 is a fragmentary, perspective view of the split end of one of the fin plates before the two parts thereof are fastened together.

Fig. 8 is a similar view showing the plate after the parts have been secured by the fastening tongue.

Fig. 9 is a fragmentary sectional elevation on line 9-9, Fig. 6.

The heater or heat exchange device shown comprises a bent or serpentine tube 10 of oblong cross section having opposite, substantially flat sides and rounded edges and joined at its ends to inlet and outlet headers or fluid

connections 11 and 12, the tube being provided on the straight portions thereof with spaced radiating fins or fin plates 13. It will be understood, however, that the invention is also applicable to heat exchange devices of other construction having one or more tubes which may be straight from end to end or of other shape, and also of other cross sectional form.

10 The fin plates are alike and surround the radiating tube 10, preferably in closely spaced parallel relation to each other. Each fin plate consists of a thin plate or sheet of metal having suitable heat conductivity such for instance, as copper, and is provided centrally with an opening 14 to receive the tube. At one place, preferably at one end, the fin plate is split as indicated at 15, (see Figs. 3, 4 and 6-8) from the tube opening to the edge of the 15 plate so that the split end of the plate can be opened or spread to permit the plate to be passed over the radiating tube laterally thereof. The tube opening 14 in the plate conforms in size and shape to the external cross 20 sectional shape of the tube, so that when the split plate has been slipped over the tube and the two parts at the split portion of the plate brought together, the edges of the opening 14 will contact throughout with the surface of 25 the tube.

Means are provided, preferably consisting of integral parts of the split end of the plate, which are adapted to secure together or hold in contiguous relation the two parts of the 30 split end of the plate after the latter has been placed on the tube, for the purpose of retaining the fin plate in place on the tube. In the construction shown, the split end of the fin plate is provided at one side of the split 35 15 with a fastening tongue 17 punched out from the body of the plate, and at the other side of the split 15 with a hole 18 through which the tongue is adapted to be passed and the end of the tongue bent over the edge of 40 the hole to thereby secure the two parts of the split end of the plate together, with the edges of the split abutting, as clearly shown in Figs. 7 and 8. The tongue being of thin metal, can be readily bent to pass through 45 the hole 18, and the parts of the tongue at opposite sides of the plate can be readily bent or pressed inwardly firmly against the opposite faces of the plate. The two parts of the plate can be thus drawn closely together 50 about the tube and held with the two parts of the split end of the plate firmly together and in the same plane with the edges of the split 15 abutting.

55 Preferably the fin plate is provided with a laterally bent flange 19 surrounding the opening 14 so as to strengthen the plate and give a greater contact area between the plate and the surface of the tube, and preferably also the plate is corrugated, as shown at 20, 60 to give an increased area of radiating surface

and also to stiffen the plate and provide tortuous passages for the air between adjacent plates.

In order to uniformly space the plates apart and hold them in the intended spaced parallel relation, each plate is preferably formed with integral spacing lugs 21 punched out from the body of the plate and adapted to contact with the faces of the next adjacent plate. These lugs are preferably tapered as 75 shown, or are of greater width at their outer ends than at their inner ends so that when placing the plates in position on the tube, the lugs of one plate cannot enter the lug openings in the adjacent plate and thus permit 80 relative displacement of the plates on the tube. By this formation of the spacing lugs, the lugs can be located in the same position on all of the plates, and yet the lugs on one plate cannot enter the lug openings in the next 85 adjacent plate, and therefore all of the plates can be the same and can be produced by the same die.

After the fin plates have been placed on the tube and retained thereon by passing the tongues through the holes 18 and bending the tongues as explained, the fin plates can be permanently fastened or soldered to the tubes, for instance by dipping the device in molten solder. Thus the fin plates will be 90 not only soldered to the tube, but the abutting edges of the split 15 will be soldered together and the fastening tongue 17 soldered to the two parts of the split end of the plate, and very strong and durable connections effected between the parts of each plate 95 and between the several plates and the tube.

I claim as my invention:

1. A single-piece fin plate for heat exchange tubes having an opening therethrough to receive the tube and being split from said opening to the outer edge of the plate whereby said plate can be placed on said tube laterally thereof, and said plate having integral parts at the split portion thereof which cooperate to hold the parts of said split portion of the plate in contiguous relation. 105

2. A single-piece fin plate for heat exchange tubes having an opening therethrough to receive the tube and being split from said opening to the outer edge of the plate whereby said plate can be placed on said tube laterally thereof, and said plate having integral parts at the split portion thereof and adjacent its outer edge which cooperate to hold the parts of said split portion of the plate in contiguous relation in the same plane and with the edges of said split abutting. 110

3. A single-piece fin plate for heat exchange tubes having an opening therethrough to receive the tube and being split from said opening to one edge of the plate, and said plate having at one side of the split 120 125 130

an integral tongue adapted to extend across said split and enter a hole in the plate at the opposite side of the split for connecting the parts of the split portion of the plate.

5. 4. A fin plate for heat exchange tubes having an opening therethrough to receive the tube and being split from said opening to the outer edge of the plate, and said plate having at one side of the split an integral tongue adapted to extend across said split and pass through a hole in the plate at the opposite side of the split, and the parts of said tongue at opposite sides of the plate being bent into contact with the opposite faces 10 of the plate to hold together the parts of the split portion of the plate with said parts in the same plane, and the edges of said split abutting.

20. 5. A heat exchange device comprising a tube, and a series of fin plates surrounding said tube and projecting outwardly therefrom in spaced relation to each other, each of said fin plates consisting of a single-piece plate having an opening through which the tube passes and being split from said opening to one edge of the plate, and means formed by integral portions of the plate adjacent the split thereof which hold the parts 25 of said split portion of the plate in contiguous relation.

25. 6. A heat exchange device comprising a tube, and a series of fin plates surrounding said tube and projecting outwardly therefrom in spaced relation to each other, each of said fin plates having an opening through which the tube passes and being split from said opening to the outer periphery of the plate, and said plate having an integral bendable tongue adjacent its outer periphery and 40 at one side of said split and adapted to cross the split and be passed through a hole in the plate at the opposite side of the split and to be bent into engagement with the adjacent parts of the plate for holding together the 45 parts of said split portion of the plate.

50. 7. A heat exchange device comprising a tube, and a series of fin plates surrounding said tube and projecting outwardly therefrom in spaced relation to each other, each of said fin plates having an opening through which the tube passes and being split from said opening to one edge of the plate, a fastener for holding together the parts of said split portion of said plate, and each plate 55 having lugs punched out from the body of the plate and adapted to engage the next adjacent plate for holding the plates in spaced relation, said lugs being of greater width at their outer ends than at their inner ends to 60 prevent the lugs of one plate from entering the lug-apertures of the next plate.

65. 8. A heat exchange device comprising a tube of elongated cross sectional form, and a series of fin plates surrounding said tube and projecting outwardly therefrom in

spaced relation to each other, each of said fin plates consisting of a single-piece plate having an elongated opening conforming to the external cross sectional form of the tube and through which the tube passes, and being split from one narrow end of said opening to the adjacent outer edge of the plate, and a fastener integral with the plate for connecting the parts of said split portion of each plate.
